(57) **CLAIM**

The ornamental design for an adjustable forehead support screw for a respiratory mask, as shown and described.

DESCRIPTION

FIG. 1 is a perspective view of a head portion of a forehead support screw for a respiratory mask according to an embodiment of our design;

FIG. 2 is a front view thereof; and,

FIG. 3 is a right side view thereof.

Where included, broken lines showing environment or structure are for illustrative purposes only and form no part of the claimed design.
